MULTIPLE DECK COT

Eugene D. Hallock, Buffalo, N. Y.

Application April 10, 1942, Serial No. 438,366

8 Claims. (Cl. 5—8)

(Granted under the act of March 3, 1883, as
amended April 30, 1928; 370 O. G. 757)

The invention described herein, if patented, may be manufactured and used by or for the Government for governmental purposes, without the payment to me of any royalty thereon.

The present invention relates to folding cot frames and more particularly to a novel and simplified structure adapted to support two or more conventional folding metal cots in multiple deck relationship, one above the other.

It may be well to point out in connection with this application that it is common practice at the present time to provide quarters for soldiers with a multiplicity of individual metal frame cots, usually of a conventional type having spring frames supported by a head frame at one end and a foot frame at the other, the arrangement being such that each of the end frames is pivotally linked to the spring frame so that the entire cot may be folded flat for storage or shipping.

The applicant is aware that the obvious space saving advantages to be derived by having these cots arranged in tiers of two, three or more decks have long been recognized and that numerous different expedients have been resorted to in an attempt to provide satisfactory multiple deck supporting means. However, so far as known to the applicant, each of these structures known in the prior art has been subject to one or more rather serious objections. Since these may be stated very briefly, it is believed proper to set them out in this application in order that the advantages inherent in the applicant's construction here disclosed may be instantly apparent. Accordingly, it may be noted that prior art structures may have been objectionable in that:

1. They have been heavy, cumbersome and bulky;
2. They have been permanently attached to the building floor or walls and thus not readily shifted to facilitate cleaning;
3. They have included screws, wing nuts, clamps or similar devices having a natural tendency to loosen and permit shifting of the cots;
4. They have been so constructed as to provide surfaces or crevices in which dirt might accumulate and which might be inhabited by vermin;
5. They have supported the upper cots directly from the floor or wall surface thereby requiring more material than the present construction;
6. They have been relatively expensive, often representing an expenditure comparable with the cost of the cots.

It is, accordingly, the aim of the present in- 55

vention to provide a novel and improved structure having none of the above faults and consequently more satisfactory in practical use than any prior art structure.

5 It may be also pointed out that while the present structure has been designed specifically to meet the needs of army troops, its utility is believed to extend to civilian uses as well and its advantages are believed to apply equally to

10 military and commercial devices.

The primary object of the invention is to provide an improved and simplified multiple deck cot support so constructed and arranged that standard types of folding metal cots may be supported in tiers to conserve space in army barracks without sacrifice of the comfort of the soldiers.

15 A further object of the invention is to provide a novel and improved multiple deck cot support so designed and constructed that the frame of the upper cot is supported directly on the main frame member of the cot immediately below; in order to eliminate the necessity of building supplemental frameworks, bulkheads, or 20 other means to support each cot frame independently.

25 A further object of the invention resides in the provision of means for supporting standard types of folding metal cots in multiple deck relationship, the means comprising four identical and separate independent corner posts, each adapted to receive one of the feet of the upper cot and to engage the lower cot frame in 30 interlocking relationship.

35 A further object of the invention is to provide multiple deck cot supports comprising a simple straight tubular body portion adapted to receive a foot portion of the upper cot at its upper extremity and to support the weight of the cot on the curved upper surface of the frame members of the lower cot.

40 Another object of the invention is to provide multiple deck cot supporting corner posts so designed and constructed as to interlock with the frame member of the lower cot and to be maintained in interlocked position at all times by the frame of the upper cot so that the tubular deck cot construction is a rigidly integrated unit and so that the lower cots may be lifted 45 from the floor by grasping the corner posts.

45 A further object of the invention is to provide a novel and improved multiple deck cot support of simple design and construction, so designed as to interlock with the standard metal frames of conventional types of cots to provide unob-

structed access to all parts of the cot frames for cleaning, and without resulting in concealed shelves, ledges, pockets, or other surfaces that might tend to collect dirt or furnish concealed breeding places for vermin.

A further object of the invention is to provide a multiple deck cot support supporting structure so designed and constructed as to be well adapted to economical methods of manufacture and of such simplicity that it may be produced at relatively small cost.

Further objects will appear hereinafter.

Referring now more particularly to the drawings:

Fig. 1 is a fragmental perspective view of a present preferred embodiment of the multiple deck cot supporting post showing the corner post in the position it assumes in a double deck tier of cots;

Fig. 2 is a perspective view of the corner post illustrated in Fig. 1;

Fig. 3 is a fragmental detail sectional view showing the interlocking relationship between a lower end of the corner post and the lower cot frame;

Fig. 4 is a perspective view of a modified form of cot supporting corner post; and

Fig. 5 is a detail sectional view of the corner post illustrated in Fig. 4.

The corner posts, generally indicated by the reference numeral 10 in Fig. 1, are provided in sets of four. Each is adapted to extend upwardly from one corner of a conventional folding cot to support an identical cot immediately above it.

The lower and upper cots both include spring frames 11 supported by head and foot frames 12. The head and foot frames are identical in construction and in the type of cot illustrated in this application each includes a straight horizontal tubular cross-bar 13 having downwardly curved side portions 14 terminating in vertical leg portions 15 joined by horizontal tie-rod 16. Both the head and foot frames are pivotally mounted on the spring frame by a pair of links 17 and 18, the links 17 and 18 extending between the rivets 19 and 20 on the spring frame and the rivets 21 and 22 on the end frame 12 of each of the cots.

The corner post structure 10 forms the essence of the present invention and comprises a straight cylindrical tube opened at its upper end and split at its lower end to provide a pair of side flanges 25 extending upwardly a short distance from the lower end of the tube and interconnected by a curved bearing surface 26 at the upper extremity of the split. The arrangement is such that the tube is entirely open on one side and may be positioned over the curved portion 14 of one of the end frames of the cot, so that the flanges 25 will fit snugly on either side of the tubular end frame and the bearing portion 26 will come to rest against the inclined upper surface 27 of the curved portion 14 of the end frame.

The opposite side of the tube 10 is notched at 28 to provide clearance around the rivet 21, but it should be noted that the downwardly extending edges 29 bounding the notch 28 and the horizontal edge 31 forming the upper limit to the notch all lie immediately behind the link 17, so that lateral movement of the lower end of the corner post 10 will be limited by the link.

From examination of Figs. 1 and 3, it will be seen that the lower extremity of the leg 15 of the upper cot is positioned in the open upper end of the tubular corner post 10 and extends down-

wardly an appreciable distance so that the tie-rod 16 of the upper cot will bear against the upper end of the corner post and form a firm support for the upper cot. In this position the leg of the upper cot frame 12 extends well into the tubular corner post 10 and thus establishes a firm and solid connection between the corner post and the upper cot.

The lower end of the corner post 10 is preferably arranged to receive its principal support by the engagement of the bearing portion 26 of the corner post with the downwardly inclined surface 27 of the curved portion 14 of the lower cot and frame. The downward thrust of the corner post will then tend to react on the inclined surface to move the lower extremity of the corner laterally outwardly to the left as viewed in Fig. 3, but this motion will be limited by the edges 31 of the notch 28, which bear against the inner surface of the link 17.

A tendency toward the camming action just described is of advantage in the present construction, however, since it tends to utilize the downward thrust due to the weight of the upper cots to exert a wedging action between the corner post and the frame of the lower cot so that the corner post end frame and link 17 are rigidly wedged together and not subject to looseness, rattling or lost motion of any kind. It is contemplated, of course, that if desired, the upper edge 31 of the notch 28 may engage the rivet 21 directly and be supported thereby but in the structure illustrated this is unnecessary.

From the foregoing, it will be apparent that the construction and arrangement of each of the corner posts is such as to provide a firm, rigid, and vibrationless support for one or more upper tiers of cots, but it is also contemplated that it may be desirable to provide a more permanent interlocking engagement between the corner posts and the lower cots so that the entire tier of the cots may be lifted by grasping the individual corner posts only, to facilitate the moving of the cots about the barracks and to prevent any possibility of accidental disengagement between the corner post and the cot on which it is supported. To this end a pair of ears 32 are provided at the lower extremities of the side edges 29 respectively of the notch 28. These ears are of sufficient length to extend below the link 17 so that straight upward movement of the corner post 10 with respect to the end frame 12 of the cot will be prevented by the engagement of the ears 32 with the lower surfaces of the link 17. Thus, as long as the upper ends of the corner post 10 are maintained in proper spaced relationship to each other, as by their engagement with the end frame of the upper cot, the lower ends of the corner posts positively interlock with the end frame of the lower cot. To release the corner posts and disassemble the structure it is necessary to first lift the upper cot out of its telescoping arrangement with the corner posts and then swing the upper ends of each of the corner posts outwardly so that the ears 32 may be passed behind the link 17.

In assembling the cots it is, of course, necessary to manipulate the corner posts in a non-vertical position to position the ears 32 behind the link 17, then swing the corner posts to vertical position and insert the feet of the upper cot in the open tubular ends at the top of the ends of each corner post.

In the modified embodiment of the invention illustrated in Figs. 4 and 5, the tubular riser 41

of the corner post is provided with an enlarged socket 42 to receive the foot of the upper cot so that its telescoping movement into the riser will be limited by the internal shoulder 43 at the lower extremity of the socket 42. The lower end of the riser 41 is welded or otherwise secured in a metal stamping 44, preferably of a generally triangular shape and comprising two gusset plates 45 and 46 respectively, joined by horizontal top portion 47 to provide, in effect, an inverted channel 48 arranged to be positioned over the tubular end frame 12 of the cot so that the lower surface of the inverted channel 48 will engage the upper surface of the straight horizontal bar portion 13 of the cot and frame.

The gusset plates 45 and 46 are joined along their lower portions by the curved portion 49 which is notched at 50 to clear the rivet 21 as hereinbefore pointed out in connection with the form of the invention illustrated in Figs. 1, 2 and 3. As in the former case, however, the edges 51, 52 and 53 may assume positions behind the surface of the links 17 to prevent lateral displacement of the corner post with respect to the end frame 12.

It will also be noted that although the illustrations of Figs. 4 and 5 do not show ears similar to the ears 32 of the previously described form of the invention, it is contemplated that these may be used or may be omitted as a matter of choice in this construction. It is to be noted in the present construction, however, that it is unnecessary to take bearing on the curved portion 14 of the lower cot frame 12, since the inverted channel 48 is positioned to rest squarely in engagement with the surface of the straight horizontal bar portion 13 of the cot frame.

From the foregoing description it should be instantly apparent that the present application discloses a highly satisfactory multiple deck cot support marking a distinct advance in the art since it overcomes the objections commonly made in prior art structures on the basis of their weight, cost, bulk, portability or complexity and provides in four single, independent and identical pieces of metal a fully efficient means for supporting multiple deck cots that combines the advantages of absolute rigidity, simplicity, attractiveness of appearance, ease in assembly and disassembly, low cost and long life.

As hereinbefore stated, the detailed structure of the present application has been developed in the United States Army to meet present military requirements and is believed to be the most satisfactory article for the purpose yet devised. It should not be considered as limited to military uses, however, since it is believed to be equally acceptable in commercial and civilian adaptation and the invention should therefore be regarded as limited only by the scope of the appended claims.

Having thus described my invention, I claim:

1. In a multiple deck cot, a lower cot structure including a spring frame, a pair of end frames at the head and foot thereof, and paired links interconnecting the spring frame and end frames; each of said end frames constituting a tubular horizontal bar extending across the width of the cot, curving downwardly adjacent each side of the cot in a curved portion, and extending vertically downwardly adjacent each corner of the cot in a vertical leg portion; an upper cot structure including a spring frame and end frames identical in design and construction with the lower cot structure heretofore defined; and four upper cot

supporting corner posts each including a socket receiving the lower end portion of one of the legs of the upper cot frame and a column extending downwardly to the lower cot frame, said corner posts having base portions supported by the horizontal bar portion of the end frame of the cot and inclosing a portion of the tubular horizontal end frame member of the cot; and means to prevent lateral shifting of the lower portions of the corner posts with respect to the lower frame elements of the lower cot, said means consisting of surfaces adapted to engage the inner side of one of the links interconnecting the end frame of the cot with the spring frame.

2. In a multiple deck cot, a lower cot structure including a spring frame and a pair of end frames at the head and foot thereof; each of said end frames constituting a tubular horizontal bar extending across the width of the cot, curving downwardly adjacent each side of the cot in a curved portion, and extending vertically downwardly adjacent each corner of the cot in a vertical leg portion; an upper cot structure including a spring frame and end frames identical in design and construction with the lower cot structure heretofore defined; and four upper cot supporting corner posts each including a socket receiving the lower end portion of one of the legs of the upper cot frame and a column to extend downwardly to the lower cot frame, said corner posts having base portions supported by the horizontal bar portion of the end frame of the cot and inclosing a portion of the tubular horizontal end frame member of the cot and means to prevent lateral shifting of the lower portions of the corner posts with respect to the lower frame elements of the lower cot.

3. In a multiple deck cot, a lower cot structure including a spring frame, and a pair of end frames at the head and foot thereof; each of said end frames constituting a tubular horizontal bar extending across the width of the cot, curving downwardly adjacent each side of the cot in a curved portion and extending vertically downwardly adjacent each corner of the cot in a vertical leg portion; an upper cot structure including a spring frame and end frames identical in design and construction with the lower cot structure heretofore defined; and four upper cot supporting corner posts each having a relatively long cylindrical tubular body portion, said body portions being open at their upper ends telescopically engaging with the lower extremities of the leg portions of the upper cot, the lower portion of each of said cornerposts being split at one side and flared outwardly to provide two opposed side flanges extending upwardly an appreciable distance from the lower extremity of the corner post and joined at their upper extremities by a curved bearing portion, the lower split portion of the corner post engaging and surrounding a portion of the tubular end frame of the lower cot so that the corner post may assume a position in vertical alignment with the vertical leg portions of the cot and so that the curved bearing surface interconnecting the side flanges of the corner post may engage and be supported by the curved portion of the end frame of the cot; and means to prevent lateral movement of the corner post with respect to the cot and to thus facilitate wedging engagement between the corner post and the inclined surface of the cot frame.

4. In a multiple deck cot, a lower cot structure including a spring frame, a pair of end frames at the head and foot thereof, and links

interconnecting the spring frame and end frames; each of said end frames constituting a tubular horizontal bar extending across the width of the cot, curving downwardly adjacent each side of the cot in a curved portion, and extending vertically downwardly adjacent each corner of the cot in a vertical leg portion; an upper cot structure including a spring frame, end frames and links identical in design and construction with the lower cot structure heretofore defined; and four upper cot supporting corner posts each having a relatively long cylindrical tubular body portion of uniform diameter throughout its entire length, each of said body portions being open at its upper end for telescopic engagement with the lower extremity of a leg portion of the upper cot, the lower portion of each of said tubular body being split at one side and flared outwardly to provide two opposed side flanges extending upwardly an appreciable distance from the lower extremity of the corner post and joined at their upper extremities by a curved bearing portion, the lower split portion of each of the corner posts engaging and surrounding a portion of a tubular end frame of the lower cot, so that the corner posts may assume positions in vertical alignment with the vertical leg portions of the lower cot and so that the curved bearing surface interconnecting the side flanges of the corner post may engage and be supported by the curved portion of the end frames of the lower cot, and means to prevent lateral movement of the corner post with respect to the cot and to thus facilitate wedging engagement between the corner post and the inclined surface of the cot frame.

5. As an article of manufacture, a multiple deck cot supporting post having a relatively long cylindrical tubular body portion, said body portion being open at its upper end for telescopic engagement with the lower extremity of a leg portion of a cot, the lower portion of said tubular body being split at one side to provide two opposed side flanges extending upwardly an appreciable distance from the lower extremity of the corner post and joined at their upper extremities, the construction and arrangement being such that the lower split portion of the corner post is adapted to engage and surround a portion of a tubular end frame of a cot so that the corner post may assume a position of vertical alignment with the vertical leg portions of the cot, and so that the corner post may engage and be supported by end frame of the lower cot.

6. As an article of manufacture, a multiple

deck cot supporting post having a relatively long cylindrical tubular body portion of uniform diameter throughout its entire length, said body portion being open at its upper end for telescopic engagement with the lower extremity of a tubular leg portion of a cot, the lower portion of said tubular body being split at one side and flared outwardly to provide two opposed side flanges extending upwardly an appreciable distance from the lower extremity of the corner post and joined at their upper extremities by a curved bearing portion, the construction and arrangement being such that the lower split portion of the corner post is adapted to engage and surround a portion of a tubular end frame of a cot so that the corner post may assume a position in vertical alignment with the vertical leg portions of the cot and so that the curved bearing surface interconnecting the side flanges of the corner post may engage and be supported by the curved portion of the end frame of the cot, and means to prevent lateral movement of the corner post with respect to the cot and to thus facilitate wedging engagement between the corner post and the inclined surface of the cot frame.

7. As an article of manufacture, a multiple deck cot support comprising a pair of generally triangular gusset plates spaced apart from each other a distance sufficient to receive a tubular end frame of a folding cot, an inverted channel portion joining said gusset plates at their upper edges; side flanges on said gusset plates to prevent lateral displacement thereof, a tubular riser portion integrally united with the gusset plates and extending upwardly therefrom, and a socket portion at the upper end of said riser to receive and support the lower extremity of the leg of an upper cot.

8. As an article of manufacture, a multiple deck cot support comprising a pair of generally triangular gusset plates spaced apart from each other a distance sufficient to receive a tubular end frame of a folding cot, an inverted channel portion joining said gusset plates at their upper edges and adapted to bear against a flat horizontal surface of the cot frame; said flanges on said gusset plates to prevent lateral displacement thereof, a tubular riser portion integrally united with the gusset plates and extending upwardly therefrom, and an enlarged socket portion at the upper end of said riser; said socket including an internal shoulder to receive and support the lower extremity of the leg of an upper cot.

EUGENE D. HALLOCK.
